Joseph L. Corbi,

INVENTOR

BY Victor J. Evans

ATTORNEY

P. J. Hickey

WITNESS:

UNITED STATES PATENT OFFICE

JOSEPH L. CORBI, OF WASHINGTON, DISTRICT OF COLUMBIA, ASSIGNOR OF ONE-THIRD
TO VICTOR GALOTTA, OF WASHINGTON, DISTRICT OF COLUMBIA, AND ONE-THIRD
TO HENRY PIZZUTIELLO, OF BRONX, NEW YORK

SHIRT

Application filed March 5, 1929. Serial No. 344,509.

This invention relates to improvements in shirts, the general object of the invention being to provide means for holding the cuff carrying portions of the sleeves of the shirt in folded and raised position on the arms of the wearer so that the cuffs will not be soiled when the wearer is washing his hands or doing work which would tend to soil the cuffs if the sleeves were not folded up on the arms of the wearer.

Another object of the invention is to so form the parts that the cuff carrying portions of the sleeves need be folded but once and the parts can be easily and quickly fastened in this position, so that there is no necessity for rolling the cuff carrying portions, which causes wrinkles in the cuff and otherwise detracts from the appearance of the cuff.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:—

Figure 1 is a view of the cuff carrying part of a shirt sleeve, showing the invention in inoperative position.

Figure 2 is a similar view, with the sleeve turned up and held in this position by the invention.

Figure 3 is a section on line 3—3 of Figure 1.

Figure 4 is a section on line 4—4 of Figure 2.

Figure 5 is a view showing a modification.

In these drawings, the numeral 1 indicates a strap which is preferably made of the same material from which the shirt is made, one end of this strap having the buttonhole 2 therein and the other end having a plurality of buttonholes 3 therein. The end which carries the buttonhole 2 may be fastened to the inside face of the lapped or

outer part 4 of the cuff by the tape 5, so that the strap will not be detached from the shirt when the same is being laundered. The buttonhole 2 is designed to receive that part of the cuff button 6 which passes through the buttonholes at that end of the cuff to which the strap is connected. That end of the strap which carries the holes 3 has attached thereto a part 7 of a snap fastener, the other part 8 of which is attached to the sleeve an appreciable distance from the cuff so that when the strap is not in use, by connecting the parts 7 and 8 of the snap fastener, the strap is held in a vertical position parallel with the slit in the sleeve, as shown in Figure 1. When the wearer wishes to wash his hands or do work which might soil the cuff, the cuff carrying part of the sleeve is folded once upon itself, as shown in Figure 2, and the strap turned to a horizontal position and connected with the other end of the cuff by a part 9 of a snap fastener button which engages another part of the button in the buttonholes at one end of the cuff. This other part of the button engages the part 9' at the other end of the cuff when the cuff is in normal position. Thus the cuff carrying portion of the sleeve can be easily and quickly folded and fastened in this position by the strap.

By providing a plurality of buttonholes 3, the part 9 of the button can be placed in any desired hole so that the strap can be adjusted to suit the size of the arm of the wearer. While the drawings show the parts connected together by snap fasteners, it will, of course, be understood that other types of buttons can be used. It will also be seen that the strap pivots on the button which passes through the hole 2 so that it can be readily turned from a vertical position to a horizontal position.

As shown in Figure 2, the strap forms an extension of the cuff when the sleeve is folded, with its ends fastened to the ends of the cuff and thus retains the sleeve and cuff in raised position on the arm of the wearer.

In the modification shown in Figure 5, the strap 1' has one end sewn to the cuff, and when the strap is not in use, its other

end is fastened by any one of a number of buttons 10 to the inside face of a part of the cuff between the two portions of the cuff, so that it is hidden from view. This position of the strap is shown in dotted lines in 5. Figure 5. When the strap is to be used to hold the sleeve in raised position on the arm, it is moved to the full line position of Figure 5 and passed around the arm, after the sleeve has been folded, and one of its but- 10 tonholes 3' placed over the cuff button 11 at that end of the cuff opposite to the end to which the strap is fastened. The inner end of the strap is formed with a buttonhole, 2' to receive the other part 11' of the cuff but- 15 ton when the device is in inoperative position.

It is thought from the foregoing description that the advantages and novel features of the invention will be readily apparent.

20 It is to be understood that changes may be made in the construction and in the combination and arrangement of the several parts, provided that such changes fall within the scope of the appended claim.

25 What I claim is:—

Means for holding a shirt sleeve in folded and raised position on the arm of a wearer, comprising a strap, means for connecting one end of the strap to one end of the cuff 30 of the sleeve, said strap having buttonholes in each end thereof for receiving portions of the cuff button, whereby the ends of the cuff are connected together by the strap and the cuff held on the upper part of the fore- 35 arm of the wearer and a button on the sleeve above the cuff and adjacent one edge of the slit in the sleeve for passing through the buttonhole at the free end of the strap to hold the strap in inoperative position.

40 In testimony whereof I affix my signature.

JOSEPH L. CORBI
